UNITED STATES PATENT OFFICE

2,263,899

APPARATUS FOR FORMING DIE CASTINGS

Louis H. Morin, Bronx, N. Y., assignor to White-hall Patents Corporation, Bronx, N. Y., a corporation of New York

Application July 10, 1940, Serial No. 344,656

10 Claims. (Cl. 22—92)

This invention relates to the formation of die castings, such for example as the slider of a separable fastener. More particularly the invention relates to an apparatus for forming what may be termed undercut portions in a casting by employing one die member composed of two parts or sections, one movable relatively to the other in forming the undercut and in releasing said section from the casting in order to remove the casting from the dies, such castings having undercut portions being formed in accordance with the method as hereinafter set forth. The novel features of the invention will be best understood from the following description and annexed drawing in which certain embodiments of the invention are disclosed and in which the separate parts are designated by suitable reference characters in each of the views and in which:

Fig. 1 is a plan and sectional view of a part of a casting machine showing the die structure employed.

Fig. 2 is a face view of the structure as seen in Fig. 1 with part of the construction broken away and in section.

Fig. 3 is a view similar to Fig. 1 showing the parts in a different position.

Fig. 4 is a view similar to Figs. 1 and 3 showing the parts in still another position.

Fig. 5 is a detail view of a product made in accordance with the teachings in Figs. 1 to 4 inclusive, and

Fig. 6 is a view similar to Fig. 5 showing a modified form of product.

In forming die castings, it has been the common practice in forming apertures, recesses, or the like, in what might be termed undercut portions of a casting, by drilling or other machine operation. In some cases this has been accomplished by the complicated procedure of employing independently operable cores which are pulled from the casting before the removal of the casting from the die impression or cavity. It is the purpose of my present invention to provide a simple, practical, as well as automatic means for forming undercut portions in die castings by employing a novel die construction wherein one of the die members is divided into independent sections or die parts relatively movable to each other in the automatic withdrawal of the undercut forming element of the die part, prior to the separation of the dies and removal of the casting from the impression or mold cavity.

In illustrating one adaptation of the invention, it has been shown as applied to the formation of undercut portions in die cast sliders, such as em-

ployed on the stringers of separable fasteners. In Figs. 5 and 6 of the drawing, two different forms of sliders are shown, whereas the die structure as seen in Figs. 1 to 4 inclusive is applicable to the formation of the slider casting 10 shown in Fig. 5. This die structure would naturally be modified slightly in forming a die cast slider such as indicated at 10a in Fig. 6. These two sliders differ from each other primarily in that the slider 10 has a channeled body 11, on the outer surface of one wall of which is a lug 12 formed with a transverse opening 13 therein, which in the present structure opens through one wall of the lug 12, as seen at 14. This latter feature is adapted primarily for detachable mounting of the conventional finger piece or pull with the slider as is well known in this fastener art.

In Fig. 6, the slider body 11a has on the outer surface of one wall thereof an elongated loop 12a in which is formed an elongated transverse aperture 13a. The apertures or openings 13, 13a constitute the undercut portions of the die castings which are to be formed in accordance with the method and apparatus as now described.

In Figs. 1 to 4 inclusive is shown the novel die structure as applied to die casting machines of the general type and kind as disclosed in my prior Patent No. 1,975,966 dated October 9, 1934. At 15 is shown one of the two reciprocating die operating rods employed in machines of this type and kind which moves transversely across the longitudinal plane of the dies in moving the dies toward and from each other. The rods 15 carry tooth-like angularly disposed cam sections 16 which move the two die members generally, indicated at 17 and 18, toward and from each other. The rod actuating the die member 18 is omitted as this structure is consistent with the conventional structure and forms no special part of the present invention.

The die members 17 and 18 when brought together form one impression or cavity 19 on the parting line 19a of said die members, of such contour as to form the slider 10 shown in Fig. 5. Upper and lower cores 20 and 21 are employed to form the channel of the slider body 11 including the connecting web 22 between the spaced walls of the body, note Fig. 5 of the drawing. The cores 20 and 21 are of the general structure disclosed in Patent No. 2,181,142 of November 28, 1939, and therefore no specific illustration or description of these cores is necessary in this case. Both of these cores are arranged on the parting line 19a of the dies and the cores are used to strip the castings from the die members 17 and

18 when separated. In separating the cores 20 and 21, the casting can be stripped from one of these cores, preferably the core 20. The cores 20 and 21 form the side openings 23 between the walls of the slider as noted in Fig. 5 of the drawing, and with the present construction, the casting material is injected into the cavity 19 formed by the die members 17 and 18 when held in engagement with each other, from a nozzle 24 through a gate passage 25 arranged on the parting line 19a of the dies and opening into one side of the cavity substantially centrally thereof. It will be understood that the metal or other casting material flows to both parts of the impression forming the spaced upper and lower walls of the resulting slider casting.

The die 17 in the construction shown is composed of two die parts 26 and 27. The part 26 is movable toward and from the die 18, whereas the part 27 in addition to moving toward and from the die 18, also has a swinging movement on a pivot 28, so that a core portion 29 on the part 27, used for forming the recess or aperture 13 in the casting 10, can be moved out of the path of the lug 12 in the manner clearly illustrated in Fig. 3 of the drawing, to permit separation of the dies 17 and 18, as will be apparent.

The parts 26 and 27 are slidably mounted in a suitable slideway 30 provided on the machine which is closed at its outer end by a plate 31. The plate is secured in position by screws as indicated at 32 in Fig. 2 of the drawing, suitable key or alignment pins 33 being employed. Two set screws 34 and 35 are employed, one for accurately guiding the die part 26 and the other for engaging a bearing plate 36 arranged adjacent the pivot portion of the part 27. At the outer end of the die part 26 is a projecting lug 37 supporting a stop screw 38 for limiting the closing movement of the die part 26 to regulate proper setting of the dies 17 and 18 one with respect to the other.

At 39 is shown a heel plate adjusted in the plate 31 through a screw 40 and retained in different positions of adjustment by screws 41. The plate 39 has a notch 39a which cooperates with the outer end 42 of the die part 27 or a facing plate 43 of hard material mounted in said end 42, as clearly illustrated. Adjacent the end 42, the die part 17 is provided with a transverse recess 44 of preferably rounded contour, clearly illustrated in the drawing and having sufficient clearance with respect to the cam sections 16 as to compensate for the slight swinging movement of the die part 27. It will be understood that the recess 44 opens through the outer surface of the die part 27 as does also an elongated recess 45 formed in the die part 26; the latter having sufficient clearance to avoid contacting engagement with the cam sections 16 in all positions of the part 26, as will be apparent.

In the operation of the machine, it will be understood that the bar or rod 15 will move in the direction of the arrow x , Fig. 1. The cams 16 will cause the die part 27 to rotate on its pivot and at the same time will move both die parts 26 and 27 into the position shown in Fig. 1, thus forming a mold or die cavity. In this position of the parts, the plate 43 is in the notch 39a of the heel 39, and the core element 29 extends into that part of the cavity from which the resulting lug 12 is formed from the casting 10. With the parts firmly held in this position, the casting material is injected through the nozzle 75 of one part of the die to move the core element

into the cavity to form a casting such as 10 in said cavity.

In the next operation of the machine the bars or rods 15 move in the direction of the arrow $x2$ of Fig. 3, and in the first stages of this operation, which are indicated in Fig. 3, the engagement of the cam sections 16 with the die part 27 will first cause this die part to swing on its pivot 28 to withdraw the core element 29 in the manner shown in said figure, and also to move the plate 43 at the outer end of the die part 27 out of the notch 39a of the heel 39. As the movement of the bar 15 continues in the direction of the arrow $x2$, the cam sections 16 will move both die parts 26, 27 to the left, while the die 18 has moved to the right, separating both dies from the casting. After this, the casting is stripped from the core parts, as previously described.

The last named position of the parts is shown in Fig. 4 of the drawing, in which figure it will appear that the outer end of the die part 27 or the plate portion 43 thereof has been moved onto the inner surface 39b of the heel plate 39, thus maintaining the die parts 26 and 27 in their open position.

In completing the cycle of operation, or in other words again moving the die parts 26, 27 into the closed position shown in Fig. 1, it will appear that both die parts 26, 27 are first moved in the direction of the die 18. At the completion of this movement, the die part 27 is swung on its axis 28 to bring the two parts 26, 27 in firm engagement with each other at the inner cavity end of said die part, or in other words, in the position shown in Fig. 1 of the drawing.

The die parts 26, 27 may be referred to as tong-like parts in the relative pivotal movement of said parts. In the construction shown, however, only one of the tong members, namely the die part 27, is movable. This construction provides a very simple and yet effective means for supporting an undercut core element in the cavity of a die and for automatically displacing this element from the cavity after the casting has been formed and before separation of the two dies which collectively form the cavity.

It will of course be apparent that while the invention has been shown as applied to the formation of certain types and kinds of castings, that these castings simply show one adaptation and use of the invention. It will further be apparent that the size and contour of the undercut core element may be modified to suit the different types of castings which are formed; Fig. 6 being illustrative of one other possible form of core element which would be required, that is to say, an element of general contour of the elongated aperture 13a. In all castings, however, it is preferred that a slight taper be provided on these core elements to permit free withdrawal thereof, particularly bearing in mind the fact that the element is swung on a pivoted member in a relatively large radius arc. Furthermore, the slight taper is desirable in any event for free removal of the element. In the present illustration the taper is somewhat exaggerated in order to clearly indicate this structural feature.

It will also be understood that my invention is by no means limited to a particular means or method of mounting and actuating the die parts as herein disclosed, as various types and kinds of operating mechanisms may be employed. However, in any event, some means will be provided to care for the automatic independent operation

into the open position as well as placing the core element in the closed or operative position.

Having fully described my invention, what I claim as new and desire to secure by Letters Patent, is:

1. In die casting machines, two relatively movable dies collectively forming a mold cavity on adjacent abutting surfaces of the dies when held in firm engagement with each other, at least one of said dies being composed of separate parts, means pivoting and keying said parts to provide swinging movement of the cavity end of one part relatively to the other part, the core element on the cavity end of said movable part extending into the cavity of said dies in forming an undercut recess in the resulting casting, means for moving both dies toward and from each other, and the means for actuating the die comprising the separate parts being in direct operative engagement with said movable part to first move said part into open position in advance of moving both parts collectively into open position to free said core element from the casting and in liberating the casting from the impression of both dies.

2. In die casting machines, two relatively movable dies collectively forming a mold cavity on adjacent abutting surfaces of the dies when held in firm engagement with each other, at least one of said dies being composed of separate parts, means pivoting and keying said parts to provide swinging movement of the cavity end of one part relatively to the other part, the core element on the cavity end of said movable part extending into the cavity of said dies in forming an undercut recess in the resulting casting, means for moving both dies toward and from each other, the means for actuating the die comprising the separate parts being in direct operative engagement with said movable part to first move said part into open position in advance of moving both parts collectively into open position to free said core element from the casting and in liberating the casting from the impression of both dies, means supporting and maintaining the movable die part in open position in initially moving both die parts into closed position with respect to the other die and thereafter automatically moving the movable die part into closed position.

3. In die casting machines, two relatively movable dies collectively forming a mold cavity on adjacent abutting surfaces of the dies when held in firm engagement with each other, at least one of said dies being composed of separate parts, means pivoting and keying said parts to provide swinging movement of the cavity end of one part relatively to the other part, the core element on the cavity end of said movable part extending into the cavity of said dies in forming an undercut recess in the resulting casting, means for moving both dies toward and from each other, the means for actuating the die comprising the separate parts being in direct operative engagement with said movable part to first move said part into open position in advance of moving both parts collectively into open position to free said core element from the casting and in liberating the casting from the impression of both dies, means supporting and maintaining the movable die part in open position in initially moving both die parts into closed position with respect to the other die and thereafter automatically moving the movable die part into closed position, and ad-

justable means checking the movement of both die parts in the direction of the other die.

4. The die structure for casting machines of the class described, said structure comprising dies movable toward and from each other with a cavity formed between adjacent abutting surfaces of said dies, one of said dies comprising elongated rod parts, means pivotally coupling said parts intermediate their ends and to key the parts against relative longitudinal movement, means guiding both of said parts for collective sliding movement toward and from the other die, means in operative engagement with one end of one of said parts to swing said part on its pivot to move the other cavity end of the part substantially parallel to the parting line at adjacent abutting surfaces of said dies, and said last named cavity end of said swingable die part having a core element extending into the die cavity and movable free of the resulting casting formed in the die cavity to provide separation of said dies.

5. The die structure for casting machines of the class described, said structure comprising dies movable toward and from each other with a cavity formed between adjacent abutting surfaces of said dies, one of said dies comprising elongated rod parts, means pivotally coupling said parts intermediate their ends and to key the parts against relative longitudinal movement, means guiding both of said parts for collective sliding movement toward and from the other die, means in operative engagement with one end of one of said parts to swing said part on its pivot to move the other cavity end of the part substantially parallel to the parting line at adjacent abutting surfaces of said dies, said last named cavity end of said swingable die part having a core element extending into the die cavity and movable free of the resulting casting formed in the die cavity to provide separation of said dies, a notched heel plate adjustably engaging the first named end of said swingable die part to insure initial swinging movement of said part in advance of sliding movement of both die parts in the separation of the dies.

6. The die structure for casting machines of the class described, said structure comprising dies movable toward and from each other with a cavity formed between adjacent abutting surfaces of said dies, one of said dies comprising elongated rod parts, means pivotally coupling said parts intermediate their ends and to key the parts against relative longitudinal movement, means guiding both of said parts for collective sliding movement toward and from the other die, means in operative engagement with one end of one of said parts to swing said part on its pivot to move the other cavity end of the part substantially parallel to the parting line at adjacent abutting surfaces of said dies, said last named cavity end of said swingable die part having a core element extending into the die cavity and movable free of the resulting casting formed in the die cavity to provide separation of said dies, a notched heel plate adjustably engaging the first named end of said swingable die part to insure initial swinging movement of said part in advance of sliding movement of both die parts in the separation of the dies, and said heel plate supporting the swingable die part in open position while both dies are in spaced relation to each other.

7. In die casting structure having complementary parts relatively movable into closed

and open position and adapted when in closed position to form a mold cavity, one of said parts being composed of a first portion and a second core-carrying portion, the core-carrying portion carrying a core element extending into the mold cavity to form an undercut recess in the casting, the core-carrying portion being mounted on and joined to the first portion and adapted to have a first movement collectively with and in the same direction as the movement of said first portion, and a second movement substantially at right angles to said direction; means engaging said core-carrying portion to effect both movements; and means to restrict the movement of the core-carrying portion to its second movement until the said core is released from the casting.

8. In die casting structure having complementary parts relatively movable into closed and open position and adapted when in closed position to form a mold cavity, one of said parts being composed of a first portion and a second core-carrying portion, the core-carrying portion carrying a core element extending into the mold cavity to form an undercut recess in the casting; means to move said portions collectively into open position, the core-carrying portion being pivotally mounted on and joined to the first portion and adapted to have a first movement collectively with and in the same direction as the movement of said first portion, and a second pivotal movement substantially at right angles to said direction; and means to effect said second pivotal movement prior to the first movement to release said core from the casting prior to collective movement of said portions into open position.

9. In die casting structure having complementary parts relatively movable into closed and open position and adapted when in closed position to form a mold cavity, one of said parts

being composed of a first portion and a second core-carrying portion, both of said portions being mounted for slideable movement on a slideway; the core-carrying portion comprising a lever pivotally joined to the first portion and adapted to have a first movement of translation collectively with and in the same direction as the movement of said first portion, and a second movement of rotation substantially at right angles to said direction, said lever carrying at one end a core element extending into the mold cavity to form an undercut recess in the casting; means engaging the other end of said lever to effect both movements; and means on said slideway to restrict the movement of the lever arm to its second movement until the said core is released from the casting.

10. In die casting structure having complementary parts relatively movable into closed and open position and adapted when in closed position to form a mold cavity, one of said parts being composed of a first portion and a second core-carrying portion; the core-carrying portion being slideably mounted, for translatory movement, on a slideway and being pivotally mounted, intermediate the ends thereof, on and joined to the first portion and adapted to have a first movement of translation collectively with and in the same direction as the movement of said first portion, and a second movement of rotation substantially at right angles to said direction, the core-carrying portion carrying at one end thereof a core element extending into the mold cavity to form an undercut recess in the casting; means engaging said core-carrying portion to effect both movements; and means on the slideway to engage the core-carrying portion and to restrict the movement thereof to its second movement until the said core is released from the casting.

LOUIS H. MORIN.
